UNITED STATES PATENT OFFICE.

STOUGHTON P. CROSS, OF HARTSDALE, NEW YORK, ASSIGNOR TO THE McCABE HANGER MFG. CO., OF NEW YORK, N. Y., A CORPORATION OF NEW JERSEY.

DOOR HANGER.

Application filed August 26, 1922. Serial No. 584,452.

To all whom it may concern:

Be it known that I, STOUGHTON P. CROSS, a citizen of the United States of America, and a resident of the town of Hartsdale, 5 county of Westchester, and State of New York, have invented certain new and useful Improvements in Door Hangers, of which the following is a specification.

This invention relates to a construction 10 for a sliding door-hanger by which the suspending bolts of the door can be more readily engaged or disengaged from the rider-bar of the door-hanger whereby installation of the door-hanger may be more conveniently made, or the door removed for 15 substitution or repair without it being necessary to take down the main portion of the hanger.

In the accompanying two sheets of drawings which form a part of this specification. 20

Figure 1 is a vertical section on the line I—I of Fig. 2 through an elevator doorway and through the track and rider-bar of a door hanger in which this invention 25 is embodied.

Fig. 2 is an elevation of the same.

Fig. 3 is an isometric view of a portion of a rider-bar showing the underside.

Fig. 4 is an isometric view of the hanger 30 bolt and washer.

Fig. 5 is a vertical section similar to Fig. 1 on the line V—V of Fig. 6, showing a modification.

Fig. 6 is an elevation of the same.

Fig. 7 is an isometric view of a portion of the rider-bar of this modification showing the underside.

Fig. 8 is a vertical section similar to Fig. 1 showing a third form.

In the form shown in Figs. 1 to 4 a track-bar 10 is suitably supported from the wall of an elevator shaft and supports balls 11, 11 which in turn support a rider-bar. The rider-bar is formed by bending along longitudinal lines so as to form an inverted V-groove 12 which connects through a vertical portion 13 with a horizontal base portion 14. The vertical portion has a perforation 15 to receive the head 16 of a hanger bolt, the shank 17 of which is received in a transverse slot 18 in the base portion of the rider-bar. This transverse slot is from the meeting edge of the base portion with the vertical portion and opens 50 into the perforation for the bolt-head in the

vertical portion. A washer 20 has a ward 21 which is wide enough to engage the entire length of one side of the bolt-head, and it has a second ward 22 which is narrow enough to pass transversely through the slot in the base portion and engage the opposite side of the bolt-head. The free edge of the rider-bar base portion has a shallow slot 23 through which the wider ward passes. As the wards engage the bolt head and the wards are engaged by the slots in the rider-bar through which they pass, the bolt is thereby restrained from turning with respect to the rider-bar, and from accidentally becoming displaced or disengaged from the rider-bar. To make the bolt more secure, a nut 24 clamps between it and the bolt head the base portion of the rider-bar and the washer. The tip of the shank of the hanger bolt screws into a plate 25 which is attached to the top of a door 26. A sill 27 underlies the door and prevents the lowering of the door conveniently as would be necessary in undertaking to disengage the door from the hanger by unscrewing the bolt 70 from the plate on the top of the door.

In the form shown in Figs. 5, 6 and 7 the hanger connection is modified so as to be applicable to use in connection with rider-bars which have been made up without this construction in view and in which there is not sufficient space for the head of the hanger bolt between the upper side of the bottom of the main portion of the rider-bar and the underside of the track-bar. In 80 this form the rider-bar consists of a main portion with an inverted V-groove 30 which connects through a vertical portion 31 with a horizontal base portion 32 and an attached hanger portion with a vertical portion 33 85 at the upper edge of which is a lip 34 which overlies the base of the main portion and a lip 35 which underlies said edge and is turned in from a perforation 36. The perforation is to receive the bolt-head and the base portion 37 of this attached hanger portion of the rider-bar has a transverse slot 38 which receives the shank of the hanger bolt and opens into the perforation from the head of the bolt. The base portion 100 on the side opposite the slot has a perforation 39 through which the wide ward of the washer passes. From this side of the base portion a tongue 40 extends vertically upward and is secured by a rivet 41 to the 110

vertical portion of the main portion of the rider-bar.

In the form shown in Fig. 8 the rider-bar has an inverted V-groove 50, which connects through a vertical portion 51 with a horizontal base portion 52. The proportions are as in the first form, but the other side is turned next to the wall, the transverse slot 53 is cut in from the free edge of the base portion and the perforation 54 for the wide ward adjoins the vertical portion of the rider-bar.

In setting up the track-bar, with the rider-bar assembled thereto, is first attached to the wall of the elevator shaft without the door. The car being opposite the doorway, the door is rested on the sill in a slightly tilted position, the heights of the hanger bolt-heads with respect to the base portion of the rider-bar are noted, and the bolts are screwed in or out of the plates on the top of the door for any necessary adjustment so that when the heads rest on the base portion of the rider-bar the door will be suspended just clear of the sill. The door is then lifted slightly and the bolt-heads are engaged with the base portion of the rider-bar. Each washer with the wards is then lifted into place and clamped in position by the underlying nut. In taking down, these steps are followed in reverse order.

What I claim as new and desire to secure by Letters Patent of the United States is:

1. In a sliding door-hanger, a hanger bolt, a rider bar the base portion of which is provided with a transverse slot receiving the

shank of the hanger bolt and is also provided with a longitudinal slot beyond the transverse slot, a washer of a width less than the width of the said base portion, said washer having a ward inset from one edge of the base portion and extending through said transverse slot into engagement with one side of the bolt head, said washer having a second ward inset from the opposite edge of said base portion and extending through said longitudinal slot into engagement with the opposite side of said bolt head, and a nut for clamping the base portion and washer between said nut and the bolt head.

2. In a sliding door-hanger, a hanger bolt, a rider bar including a main portion and an attached hanger portion having a lip which overlies an edge of the main portion and a lip which underlies said edge and is turned in from a perforation to receive the bolt head, such hanger portion having a base provided with a transverse slot receiving the shank of the hanger bolt and with a second slot spaced from the transverse slot, a washer having a ward inset from one edge of the base and extending through said transverse slot into engagement with one side of the bolt head and having a second ward inset from the opposite edge of the base and extending through said second slot into engagement with the opposite side of the bolt head, and a nut for clamping the base and washer between said nut and the bolt head.

STOUGHTON P. CROSS.
